UNITED STATES PATENT OFFICE.

JESSE C. MARTIN, JR., OF SAUSALITO, CALIFORNIA

LOCOMOTIVE-FIRE-BOX CONSTRUCTION.

1,259,030.

Specification of Letters Patent. Patented Mar. 12, 1918.

Application filed March 4, 1916. Serial No. 82,207.

To all whom it may concern:

Be it known that I, JESSE C. MARTIN, Jr., a citizen of the United States, residing at Sausalito, in the county of Marin and State 5 of California, have invented certain new and useful Improvements in Locomotive-Fire-Box Construction, of which the following is a specification.

The hereinafter described invention relates to that class of fire boxes employed 10 in connection with the locomotive type of fire box boilers, and more particularly to locomotives using oil as the fuel medium.

One of the objects of the invention is to 15 provide end walls that will remain intact and not be shaken down by the vibration and the jar in service attendant the use of the locomotive and to so construct the end walls that only a minimum amount of refractory material is required in the construction 20 thereof; another object being to eliminate the labor of building as well as the expense of maintaining the end wall and in so constructing the same of interlocking units in order that the said walls 25 may be quickly assembled and with the least possible amount of labor and worn or damaged parts thereof quickly removed for repair purposes.

To comprehend the invention, reference 30 should be had to the accompanying sheets of drawings, wherein—

Figure 1 is a broken transverse sectional view of a locomotive fire box with the fire 35 pan depended therefrom, illustrating the flash end wall for the fire pan extended into the fire box a distance above the mud ring thereof, and the insulating lining interposed between the refractory walls of 40 the said pan and the inner metallic walls thereof.

Fig. 2 is a perspective view of the built-up 45 flash end wall, disclosing the unit system of construction for the interlocking vertically disposed tile members thereof.

Fig. 3 is a similar view of the front end wall for the fire pan.

Fig. 4 is a longitudinal sectional view 50 taken on the irregular line $\alpha-\alpha$ —Fig. 1 of the drawings.

In the drawings, the numeral 1 is used to 55 designate an open bottomed fire box of a locomotive type fire box boiler, and 2 a metallic fire pan secured to and depending from the said fire box, the said fire pan being suitably shaped for the work required.

The said fire pan is provided with side walls 3 and the bottom wall or floor 4 constructed of the usual refractory material, and further provided with the flash end wall 5 and 60 forward end wall 6, and there is interposed between the said walls 3, 4, 5 and 6 and the inner metallic wall of the fire-pan liner 7 constructed of any suitable insulating material, as, for instance, infusorial earth, as 65 asbestos, magnesia, etc.

By the use of the insulating liner for the fire pan heat losses by radiation are reduced to a minimum and by reason thereof lighter refractory walls may be employed than com- 70 monly used.

The sides and bottom walls for the fire pan are formed of refractory bricks laid or built up in the ordinary manner, but the end walls are differently constructed. These 75 said end walls are formed of vertically disposed tiles, each consisting of a series of transverse unit sections a . The corner tiles A of each end wall are preferably inwardly inclined from top to bottom to receive there- 80 between the wedge tile B . Preferably the unit members of the end wall tiles are formed with the interlocking tongues and grooves b , b' , and each of the corner tile units on the inner face thereof provided 85 with vertical groove c to receive the interlocking tongue c' outwardly projected from the unit members of the wedge tile B .

In the form of the fire pan 2 illustrated 90 there is provided a flanged side wall extension 8, and in such case the flash end wall is provided with outwardly extended shoulder extensions 9 which bear on the said flange sections 8.

The unit members of the end walls 5 and 95 6 are held interlocked one to the other so as to form a unit wall, and the corner tile members of the said walls are held securely and firmly in place relative to the side walls of the fire pan by means of the wedge tile 100 members, and said end walls are held in vertical position by means of the refractory sides and bottom walls 3 and 4, inasmuch as the brick work of the said walls bears against the inner face of the end walls. 105

Inasmuch as the tiles composing the end walls are constructed of a series of small unit members, the same are easily constructed or built up within the fire box structure of the locomotive, inasmuch as the unit 110 members being comparatively small they are easily passed into the fire box through the

door opening thereof, and are easily removed therefrom for purpose of repairing said end wall sections.

The flash end wall is the one which receives the hardest wear, due to the fact that the flame from the burner 10 impinges directly thereon, hence it is of great advantage in connection with fire boxes of the described type that the wall be so constructed as to permit of quick repair work.

The said flash end wall extends well within the fire box proper to a distance somewhat above the mud ring 11, in order to thoroughly protect the same.

By constructing the end walls in the manner described and holding the same in position relative to the metallic end walls of the fire pan by means of the refractory sides and bottom walls of the fire pan, the said end walls may be constructed much lighter than when formed of brick work construction, for in such case the walls must be of heavy construction in order to provide against falling down under the vibratory strains placed thereon.

Having thus described the invention, what is claimed as new and desired to be protected by Letters Patent is:—

In combination with an open bottom oil

burning locomotive type fire box, of a metallic fire pan having downwardly inclined side walls united to and depending from said box, refractory sides and bottom walls for the fire pan, a removable flash end wall and opposing end wall fitted within said pan and held in place therein intermediate the ends thereof and the ends of the sides and bottom walls, said end walls being composed of corner tiles and an intermediate wedge tile adapted to interlock one with the other, and each consisting of a series of superimposed interlocked independent unit members having angularly disposed end walls, the angle of the outer ends of said corner tiles corresponding to the inclination of the fire pan side walls and the inner ends thereof corresponding to the taper of the side walls of said wedge member whereby a three unit construction may be employed, the flash end wall extending from the bottom of the fire pan to a point within the fire box above the mud ring thereof.

In testimony whereof I have signed my name to this specification in the presence of a subscribing witness.

JESSE C. MARTIN, JR.
